PORTABLE HOT-WATER RADIATOR

Golden C. Prosser, Bloomfield, Iowa

Application May 23, 1940, Serial No. 336,836

4 Claims. (Cl. 237—17)

This invention relates to portable hot-water radiators or heating units, and has for one of its objects the production of a simple and efficient unit which may be moved from place to place in a building to heat the area where heat may be desired.

A further object of this invention is the production of a simple and efficient portable radiator or heating unit wherein a removable gas or fuel tank is carried by the unit, so that the tank may be renewed or replaced when desired, thereby eliminating the necessity of permanent connection of the unit with a fixed source of fuel supply.

Other objects and advantages of the present invention will appear throughout the following specification and claims.

In the drawing:

Figure 1 is a side elevational view of the portable radiator;

Figure 2 is an end elevational view thereof;

Figure 3 is a longitudinal sectional view taken on line 3—3 of Figure 2.

Figure 4 is a vertical sectional view taken on line 4—4 of Figure 3;

Figure 5 is a vertical sectional view taken on line 5—5 of Figure 3;

Figure 6 is an enlarged fragmentary sectional view taken on line 6—6 of Figure 2.

By referring to the drawing, it will be seen that 10 designates the frame which comprises a base 11 and a vertically extending portion 12 projecting at right angles to the base 11 at one end thereof. A series of radiator heating coils 13 is mounted upon the frame 10 in the manner shown in Figure 1.

The base 11 is provided with a fuel tank-receiving compartment 14 in which is mounted a removable fuel tank 15, which tank may rest upon the cradles 16. The base 11 is preferably supported upon a plurality of rubber-tired ball-bearing casters C to facilitate the moving of the portable radiator heating unit from place to place, whereby the desired area within a building may be conveniently heated by moving the radiator to the desired position. The tank 15 is provided with an upwardly extending burner 17 at one end and a suitable valve 18 is provided to control the passage of fuel from the tank 15 to the burner 17. A door 19 is hingedly secured at one end of the compartment 14 near the burner 17 to facilitate lighting, and side doors 20 may be provided adjacent the compartment 14 to facilitate the placing of the tank 15 in position, or the removal thereof from the

portable radiator when desired. Suitable windows 21 and 22 are placed in the doors 19 and 20 respectively.

The vertically extending portion 12 of the frame 10 carries a water heating tank 23 in suspended relation above the burner 17, the tank 23 having a concave lower face 24 just above the burner 17 to cause the flame from the burner 17 to spread outwardly and thereby take advantage of a maximum heating capacity. The tank 23 is connected to the upper end of the series of radiators 13 by means of an upwardly extending pipe 25 and is connected to the lower end of the series of radiators 13 by means of a pipe connection 26, as shown in Figure 3.

A reservoir tank 27 is carried within the vertically extending portion 12 upon one side of the pipe 25 and communicates with the water heating tank 23 by means of a pipe 28 whereby water may be admitted or supplied to the tank 23 by opening a suitable valve 29. A drain-off cock 30 is carried by the lower end of the tank 27, and the tank 27 is also provided with a filling opening 31 at the top thereof which is closed by a suitable cap.

A blow-off tank 32 is carried within the vertically extending portion 12 to one side of the pipe 25 and opposite the tank 27, and this blow-off tank 32 is connected to the upper end of the series of radiator coils 13 by a blow-off cock 33 mounted within the tank 32 so as to provide a pressure relief for the radiator coils 13 should excess pressure become accumulated in the radiator coils 13. The outer radiator coil 13 is provided with an air cock 34 of the conventional type. The tank 32 is provided with a drain-off cock 35 at the bottom thereof.

From the foregoing description, it will be seen that a very simple and efficient portable radiator or heating unit has been provided whereby a removable fuel supply tank such as a "Philgas" tank or other fuel reservoir may be renewed from time to time thereby avoiding the necessity of permanently attaching the burner 17 to a fixed fuel supply line. Consequently, the radiator or heating unit may be conveniently rolled from place to place through the medium of the casters C and thereby enable the heating unit to supply heat to a desired area, and the heating unit may be changed from place to place as desired.

An important feature of the present invention is the assembly and design of the device whereby a maximum heating capacity is provided within a minimum space and whereby a sufficient sup-

ply of water is maintained in the reservoir 21 and means is also provided to take care of an oversupply of pressure within the radiator. Furthermore, by extending the pipe 25 upwardly between the pipes 27 and 32 this pipe will be braced and the heating tank 23 because of its connection will be firmly supported within the upwardly extending portion 12. Furthermore, a minimum amount of water is carried within the tank 23 thereby providing a complete and proper circulation and avoiding the necessity of subjecting the heating element to a large area to be heated by the burner.

It should be understood that certain detail changes may be employed in the construction of the present device, without departing from the spirit of the invention, so long as such changes fall within the scope of the appended claims.

Having described the invention, what I claim as new is:

1. A portable radiator, heating unit and the like, comprising a series of heating coils, a frame supporting the coils, said frame having a fuel tank-receiving compartment extending longitudinally below the coils, a removable fuel tank extending longitudinally within the compartment, an upwardly extending burner carried by the tank at one end thereof, a vertically extending portion carried by one end of the frame, a water heating tank mounted in the vertically extending portion above said burner and communicating with the bottom of said heating coils, a return pipe connected to the upper end of the coils and communicating with the tank, a water reservoir carried above the tank and communicating with the tank, means for controlling the supply of water from the reservoir to the tank, a blow-off relief tank communicating with the upper end of the coils to relieve excess pressure from the coils, and a drain for the relief tank.
2. A portable radiator, heating unit and the like, comprising a series of heating coils, a frame supporting the coils, said frame having a fuel tank-receiving compartment extending longitudinally below the coils, a removable fuel tank extending longitudinally within the compartment, an upwardly extending burner carried by the tank at one end thereof, a vertically extending portion carried by one end of the frame, a water heating tank mounted in the vertically extending portion above said burner and communicating with the bottom of said heating coils, a return pipe connected to the upper end of the coils and communicating with the tank, a water reservoir carried above the tank and communicating with the tank, means for controlling the supply of water from the reservoir to the tank,

a blow-off relief tank communicating with the upper end of the coils to relieve excess pressure from the coils, a drain for the relief tank, and supporting casters for said frame for facilitating the removal of the radiator from place to place. 5

3. A portable radiator, heating unit and the like, comprising a series of heating coils, a frame supporting the coils, said frame having a fuel tank-receiving compartment extending longitudinally below the coils, a removable fuel tank 10 extending longitudinally within the compartment, an upwardly extending burner carried by the tank at one end thereof, a vertically extending portion carried by one end of the frame, a water heating tank mounted in the vertically extending portion above said burner and communicating with the bottom of said heating coils, a return pipe connected to the upper end of the coils and communicating with the tank, a water reservoir carried above the tank and communicating with 15 the tank, means for controlling the supply of water from the reservoir to the tank, a blow-off relief tank communicating with the upper end of the coils to relieve excess pressure from the coils, a drain for the relief tank, supporting elements 20 for said frame for facilitating the moving of the frame from place to place, a door carried by the frame to provide access to the burner, and a door communicating with the fuel tank-receiving compartment to facilitate the placing of the tank 25 within the fuel tank-receiving compartment and the removal of the tank therefrom.

4. A portable radiator, heating unit and the like, comprising a series of heating coils, a frame supporting the coils, said frame having a fuel 35 tank-receiving compartment extending longitudinally below the coils, a removable fuel tank extending longitudinally within the compartment, an upwardly extending burner carried by the tank at one end thereof, a vertically extending 40 portion carried by one end of the frame, a water heating tank mounted in the vertically extending portion above said burner and communicating with the bottom of said heating coils, a return pipe connected to the upper end of the coils and 45 communicating with the tank, a water reservoir carried above the tank and communicating with the tank, means for controlling the supply of water from the reservoir to the tank, a blow-off relief tank communicating with the upper end of the 50 coils to relieve excess pressure from the coils, a drain for the relief tank, said water reservoir and blow-off relief tanks being spaced upon opposite sides of said return pipe, and said water heating tank having a concave under face located 55 above said burner.
